UNITED STATES PATENT OFFICE.

CHARLES M. HAYDEN, OF SOUTH THOMASTON, MAINE, ASSIGNOR TO HIMSELF, AMOS FISK, AND FREDERICK S. HAYDEN, ALL OF SAME PLACE.

RIGGING OF VESSELS.

SPECIFICATION forming part of Letters Patent No. 438,076, dated October 7, 1890.

Application filed January 28, 1890. Serial No. 338,346. (No model.)

To all whom it may concern:

Be it known that I, CHARLES M. HAYDEN, of South Thomaston, in the county of Knox and State of Maine, have invented a new and useful Improvement in the Rigging of Vessels, of which the following is a full, clear, and exact description.

My invention relates to an improvement in the rigging of vessels, and has for its object 10 to prevent the mast-hoops from clinging to the mast when the sail is raised, and to cause all the hoops to sustain an equal strain, thereby avoiding all danger of tearing the sail.

The invention consists in the novel construction and combination of the several parts, as will be hereinafter fully set forth, and pointed out in the claims.

Reference is to be had to the accompanying drawing, forming a part of this specification, 20 which drawing represents a side elevation of a sail fitted to a mast and embodying my improvement.

The sail 10 is fitted with any form of mast-hoop 11 in the usual way, and upon the fore 25 side of the mast 12, at or near the saddle, one end of a rope or chain 13 is made fast, which rope is carried upward and secured to each of the hoops 11, the upper end of the rope being firmly attached to an eye in the gaff-bail 30 14, the said bail being preferably provided with a friction-roller 15, or a shoe bearing against the mast and adapted to assist in elevating the sail. The rope 13 may be attached to the mast-hoops in a number of ways. The 35 preferred connection, however, consists in screwing into the mast-hoops screw-eyes and twisting or clamping the ropes in said eyes.

If in practice it is found desirable, two ropes may be employed, in which event one 40 is located at each side of the mast and attached to opposite sides of the mast-hoops, the lower ends of the ropes being secured to the saddle and the upper ends to the jaws of the gaff, or the single rope 13 may be spliced

at the upper hoop and the ends secured to the 45 jaws of the gaff.

The halyards are run in the usual manner, the peak-halyard 19 being secured to the peak of the gaff and rove through a block secured to the mast and led downward to the 50 deck, the throat-halyard 20 being attached to the throat of the gaff and rove also through a block and carried downward to the deck, as illustrated.

By connecting all the mast-hoops in the 55 manner above described they are held horizontally or at a right angle to the inner edge of the sail, and are prevented from binding against the mast when the sail is elevated, and thereby retarding the upward movement of 60 the sail and endangering the safety thereof.

When the two ropes or chains 13 and 16 are employed to connect the mast-hoops, the friction roller or shoe may be omitted from the gaff-bail.

Having thus described my invention, I claim as new and desire to secure by Letters Patent—

1. The combination, with a sail, the mast-hoops, the gaff provided with a bail, and the 70 mast, of a rope or chain attached at one end to the mast and also attached to each of the mast-hoops, the upper end of said rope or chain being attached to the gaff-bail, substantially as and for the purpose specified. 75

2. The combination, with a sail, its mast-hoops and gaff, of a mast, a bail attached to the gaff, provided with a friction-roller bearing against the mast, and a rope or chain secured at one end to the mast at or near the 80 saddle and connected with each of the mast-hoops, the upper end of said rope or chain being secured to the gaff-bail, substantially as and for the purpose specified.

CHARLES M. HAYDEN.
